United States Patent

Des. 241,508
Patented Sept. 21, 1976

241,508

CONTOURED HANDLE

Donald L. Agate, 4531 Parkway Drive,
Hobe Heights, Fla. 33455

Filed Dec. 20, 1974, Ser. No. 535,121

Term of patent 14 years

Int. Cl. D8—01

U.S. Cl. D8—147

FIG. 1 is a top plan view of a contoured handle showing my new design;

FIG. 2 is a front elevational view taken generally along line 2—2 of FIG. 1;

FIG. 3 is a side elevational view taken generally along line 3—3 of FIG. 2;

FIG. 4 is a rear elevational view taken generally along line 4—4 of FIG. 3; and

FIG. 5 is a side view opposite that of FIG. 3 taken generally along line 5—5 of FIG. 4.

I claim:

The ornamental design for a contoured handle, as shown.
